(57) **CLAIM**

The ornamental design for a radio transmitter and battery housing adapted to engage a digital processing device, as shown and described.

DESCRIPTION

FIG. 1 is a perspective view of a first embodiment of a radio transmitter and battery housing adapted to engage a digital processing device showing my new design

FIG. 2 is a top plan view thereof;

FIG. 3 is a bottom plan view thereof;

FIG. 4 is a front elevational view thereof;

FIG. 5 is a right elevational view thereof;

FIG. 6 is a back elevational view thereof;

FIG. 7 is a left elevational view thereof;

FIG. 8 is a perspective view thereof including, in broken lines, a digital processing device shown in use;

FIG. 9 is a perspective view of a second embodiment of a radio transmitter and battery housing adapted to engage a digital processing device showing my new design;

FIG. 10 is a top plan view thereof;

FIG. 11 is a bottom plan view thereof;

FIG. 12 is a front elevational view thereof;

FIG. 13 is a right elevational view thereof;

FIG. 14 is a back elevational view thereof;

FIG. 15 is a left elevational view thereof;

FIG. 16 is a perspective view thereof including, in broken lines, a digital processing device shown in use.

The broken lines shown in the drawings form no part of the claimed design.
